UNITED STATES PATENT OFFICE.

WILLIAM M. PATTERSON, OF GREENVILLE, SOUTH CAROLINA.

REPAIR DEVICE FOR LOOM-SWORD BEARINGS.

1,324,516.

Specification of Letters Patent.

Patented Dec. 9, 1919.

Application filed May 17, 1919. Serial No. 297,803.

To all whom it may concern:

Be it known that I, WILLIAM M. PATTERSON, a citizen of the United States of America, and a resident of Greenville, 5 county of Greenville, and State of South Carolina, have invented certain new and useful Improvements in Repair Devices for Loom-Sword Bearings, of which the following is a full and clear specification.

10 This invention is designed to supply a simple repair part for the bearings of the usual bearing-pin of loom swords. These bearing-pins are usually mounted eccentrically for rotative adjustment, and the housings for the ends of the bearing-pin are cast integral with the frame. The strain is so constant and so great on these bearings that it frequently happens that the cast housings will fracture and break off. This 15 necessitates junking the entire casting, thus entailing considerable delay due to stoppage of the loom and also the loss of the value of the casting. It is the object of my invention to supply a simple repair part 20 which will serve as a substitute for the broken-off piece of housing, as more fully hereinafter set forth.

In the drawings—

Figure 1 is a perspective view of part of a 30 loom showing the usual form of bearing-pin for the sword;

Figs. 2, 3, 4, 5 and 6 are detail views showing the application of my invention.

In the drawings, *a* designates the usual 35 sword bearing-pin whose eccentric cylindrical end members *b* and *c* are journaled in the usual cast housings *d*. This bearing-pin is held in its rotative adjustments by means of set-screws *e* tapped down through 40 the respective housings, the eccentric bearing *c* being provided with an annular row of holes *f* for the reception of the inner ends of a set-screw, to thereby positively lock the bearing-pin in its adjusted position.

45 In Fig. 2, the housing is shown broken, this fracture of the housing at the point indicated being a common occurrence. This fracture invariably results in complete detachment of the top of the housing, as 50 shown, thereby exposing the cylindrical face of the eccentric bearing *c*. When a fracture of this sort occurs, it is customary to remove the casting from the machine and

junk it, as there has heretofore been no way of repairing it. In order to avoid this 55 waste of the casting and the consequent stoppage of the loom, I provide an attachable device consisting of a bar *g* adapted to be secured to the casting at one end by a bolt *h* tapped to the end of the bar and into 60 the casting. The inner face of the bar is provided with an inclined shoulder *i* which bears against a shoulder *j* formed in the casting. The bar lies against the side of the housing and against the end of the eccentric bearing *c*, and the end of the bearing opposite the bolt *h* is provided with an inwardly-extending hook *k* which is adapted to enter any one of the holes *f* in said eccentric bearing. When this bar *g* is thus 70 bolted in position on the casting, with the shoulder *i* in engagement with the shoulder *j* of the casting and its hook *k* in engagement with one of the holes *f*, the bearing-pin will be rigidly held in the housings notwithstanding the fact that one of the housings is broken away as illustrated. By 75 loosening the bolt *h* and swinging the bar *g* thereon as a pivot, the hook *k* may be released from the hole *f*, so that the bearing-pin may be rotatively adjusted in the same 80 manner as when it is clamped solely by the usual set-screws *e*.

It is desirable, in order to prevent the bar *g* from turning on the bolt *h*, to provide the 85 same with flanges *m* to engage the adjacent parallel edges of the casting; and it may be further desirable to use an additional bolt *n* for this purpose.

The nature and scope of the invention 90 having been thus indicated and its preferred embodiment having been specifically described, what is claimed as new is:

1. In a device of the class set forth, a casting having a pin journaled in housings 95 therein, and a device for repairing one of the housings, the top of which has been broken off, consisting of a bar adapted to be fastened to the casting at one end and adapted at its other end to engage into and hold 100 the exposed journal of the bearing-pin.

2. A repair device of the class set forth, consisting of a bar having a bolt-hole at one end, a shoulder intermediate its ends, and a hook formed at the other end, for the pur- 105 pose set forth.

3. In a device of the class set forth, a casting having a pin journaled in the housings thereof, one of the journals of said pin being provided with a series of holes and 5 one of the housings having its top notched to expose said series of holes, and a bar adapted to be fastened to the casting at one

end and adapted at its other end to lie in said notch and engage in one of the exposed holes in the journal pin. 10

In testimony whereof I hereunto affix my signature.

WILLIAM M. PATTERSON.
